(57) **CLAIM**

The ornamental design for a USB cap, as shown and described.

DESCRIPTION

FIG. 1 is a front perspective view of a USB cap showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a top view thereof in an exemplary use environment.

The broken line showings of the portions of the USB cap in FIGS. 1-8, and the dash dot line showing of the arm in FIG. 8, are included for the purpose of illustrating environmental structure and form no part of the claimed design.
